UNITED STATES PATENT OFFICE.

LEWIS D. DOZIER, OF ST. LOUIS COUNTY, JOHN W. GREEN, OF ST. LOUIS, AND FRANCIS J. GRINDLER, OF PINE LAWN, MISSOURI, ASSIGNORS TO PAWNEE WOOD HEEL CO., OF ST. LOUIS, MISSOURI, A CORPORATION OF MISSOURI.

METHOD OF MAKING WOOD HEELS FOR SHOES.

Application filed February 17, 1927. Serial No. 168,905.

This invention relates to a method of making wooden heels for shoes of the type having concave upper ends and tapering bodies.

An object of the invention is to provide a method for making wooden heels of the type mentioned, which method advances beyond the present practice in a manner resulting in considerable saving and avoiding the loss incident to shaping heels by the present practice. According to the present practice with which we are familiar, the concavities are formed in the upper ends of the heels after the bodies of the heels have been shaped, so that the strains and stresses caused by cutting the concavities are exerted upon the slender heel bodies resulting in considerable numbers of heels being broken or damaged.

Our improved method for obtaining these advantageous results may be clearly understood from the following description, taken in connection with the accompanying drawing, wherein

Fig. 1 is a side elevation of a wooden block from which a wooden shoe heel is made by our improved method.

Fig. 2 is a perspective view of the same block after being marked to indicate the approximate dimensions and position of the concavity to be formed in the upper end of the shoe heel.

Fig. 3 is a perspective view of the wooden block after the concavity has been formed in its upper end.

Fig. 4 is a vertical sectional view of the wooden block after it has been doweled and the concavity formed in its upper end preparatory for the final operations.

Fig. 5 is a side elevation of the block after the breast wall of the heel has been formed and before the remaining portion of the heel body has been turned to finished shape.

Fig. 6 is a view showing the heel clamped in the machine by which the final operations are performed.

Fig. 7 is a perspective view of the completed heel.

In the manufacture of wooden heels according to this invention, wooden blocks are formed with an inclined rear wall 1 and an approximately straight front wall 2, both of which are cut transversely of the grain of the wood while the top wall 3, bottom wall 4 and side walls 5 extend in the direction of the

grain. The top wall 3 and bottom wall 4 are usually flat and approximately parallel with each other.

The block is cut to form the concavity 6 in the upper end 3 of the block before the block is cut or shaped to form the slender lower heel portion. A border defining the area of the concavity to be formed may be marked on the wall 3, as indicated at 6^a, before beginning cutting the block to form the concavity. We prefer also to insert a dowel pin 7 in an inclined hole formed in the block 4 and extending upwardly from the bottom end 4. This hole may be formed and the dowel pin 7 inserted therein either before or after the concavity 6 is formed in the upper end of the block. This dowel pin extends in an inclined direction so that, when the heel is finished, the dowel pin throughout its length will be imbedded in the heel approximately axially. The dowel pin extends transversely of the wood grain to prevent splitting. It is very tight in the hole and may be additionally secured to the walls of the hole by glue.

After formation of the concavity 6 and insertion of the dowel 7 in the block, the vertical wall 2 which is across the grain of the block is cut away to form the upwardly and rearwardly inclined breast wall 8 of the heel and to provide a forward extension 9, due to the upward and forward curvature of the wall 8. By reference to Fig. 5, from which the final shape of the finished heel body, as shown in Figs. 6 and 7, may be fairly visualized, it will be seen that the dowel 7 extends obliquely upwardly and rearwardly and approximately axially in the heel body and transversely of the wood grain and, therefore, affords the necessary reinforcing strength to permit the heel body to be turned and finished without likelihood of breaking. After the breast wall 8 has been formed, the heel is clamped rigidly between an upper clamping element 9 and a lower clamping element 10 and is cut and trimmed to shape by cutters 11. The lower clamping element 10 fits somewhat closely in the concavity 6, the heel being in inverted position. The pressure of the clamping elements is transversely of the grain of the wood and we have found that, by providing the rounded clamping element 10 which is received in the concavity 6 and which substantially fills the concavity,

a very small percentage of these heels are broken by operation of the cutters 11. By experience, we have found that a much smaller percentage of heels are broken by this 5 operation than were broken by use of the old method and practice. Then, the machine holding the heel block in this novel manner, after formation of the concavity 6, is operated to turn and shape the heel to finished 10 form, the outer wall of which appears slightly concave when viewed from any lateral direction.

This provides a heel having a concave upper end and a relatively small lower body 15 portion of appropriate configuration made without danger of breaking and ready for the application of the heel cover.

In practice, we have found that this method of finishing heel bodies largely reduces the 20 number and proportion of heels that are broken during the course of manufacture. By the existing method, we estimate that there is a loss due to breakage of approximately five per cent of the total number of 25 heels finished; whereby by this method, this loss is practically eliminated.

What we claim and desire to secure by Letters Patent is:—

1. The method of making a wooden shoe 30 heel which consists in forming a concavity in the side of a wooden block that is to be at the upper end of the heel, then cutting the block to form the breast wall of the heel, then clamping the heel between two clamping 35 elements, one of which engages in said concavity and the other of which clamps against the opposite end of the heel, and then turn-

ing and cutting the heel to provide a tapered heel body.

2. The method of forming a wooden heel 40 which consists in forming a concavity in the side of a wooden block that is to be the upper end of the heel, imbedding a dowel pin in the heel body from the opposite side of the block that is to form the lower end of the 45 heel, then cutting the block to form the breast wall of the heel, and then turning and cutting the heel to form outer walls inclining downwardly and inwardly from the upper end of the heel. 50

3. The method of making a wooden heel which consists in forming a concavity in the upper end of the heel, forming the breast wall of the heel, clamping the heel between two clamping elements, one of which is engaged 55 in said concavity and the other of which clamps against the opposite end of the heel, and then turning and cutting the heel to form a tapered heel portion.

4. The method of making a wooden heel 60 which consists in forming a concavity in the upper end of the heel, forming the breast wall of the heel, imbedding a dowel pin in the heel below said concavity, clamping the heel between two clamping elements, one of which is engaged in said concavity and the other of which clamps against the opposite end of the heel, and then turning and cutting the heel to form a tapered heel portion 65 in which said dowel pin is approximately axi- 70 ally imbedded.
